UNITED STATES PATENT OFFICE.

GEORGE V. C. VREELAND, OF EAST ORANGE, NEW JERSEY, ASSIGNOR TO NATIONAL CARBON COMPANY, INC., A CORPORATION OF NEW YORK.

FLASHLIGHT.

1,374,411.

Specification of Letters Patent. Patented Apr. 12, 1921.

Application filed November 22, 1919. Serial No. 339,791.

To all whom it may concern:

Be it known that I, GEORGE V. C. VREELAND, a citizen of the United States, residing at East Orange, in the county of Essex and State of New Jersey, have invented certain new and useful Improvements in Flashlights, of which the following is a full, clear, and exact description.

The present invention has for its objects 10 the provision of a flashlight in which means is provided for establishing a circuit from the central pole of the battery and for breaking this circuit when it is desired to light or extinguish the lamp. In order to 15 control the flow of current I provide a simple switch mechanism which is of such character that it may be cheaply manufactured and assembled in the flashlight casing.

Other objects of my invention reside in 20 the provision of a cross member within the casing which is permanently maintained in position therein and adapted to abut against the uppermost battery and hold the same in position. This cross member also is adapted 25 to form a support for the cooperating fixed and movable contacts of the switch mechanism and hold the same in position. One of the elements of the switch is also adapted to 30 form a resilient contact for the lamp terminal thereby avoiding undue stress upon the lamp base and preventing damage to the lamp when the latter is inserted in the socket or under other conditions which arise when 35 flashlights are in service.

In the drawings:

Figure 1 shows a side view of my improved flash light. Certain parts are shown in central section to show the interior construction.

Fig. 2 is a similar side view taken at right angles to Fig. 1.

Fig. 3 is a sectional view of the device as shown in Fig. 1, the section being taken on line 3—3.

The flashlight comprises a tubular metal casing 10 open at both ends and having the lower end closed by a closure 11 which fits within the casing and is secured in position by a bayonet lock 12. The closure 11 carries 5 a coil spring 13 which serves to conduct current from one electrode of the battery 13 to the conducting casing. The upper end of the casing has a reflector 14 therein, the reflector fitting tightly in the end of the casing 55 and being held by the friction-engagement of the casing end and reflector side walls.

The reflector carries the usual lamp socket 15.

Just above the top of the battery I provide a U-shaped cross member or saddle 16 which is retained in position in the tube by rivets. This cross member is of metal and rigid. Upon the upper side of the cross member is placed a strip of insulation 17 and upon the lower side is a similar strip 18, and below strip 18 is a metal contact spring 19. To retain the insulating strips, cross member and contact spring together, whereby the strips and contact spring may be supported by the cross member, I provide a pair of eyelets 20 which pass through enlarged holes in the cross member without contacting with the edges thereof. In this manner the current from central pole 21 of the battery is prevented from flowing to the cross member 16. The contact spring 19 makes contact with the central pole of the battery and extends up past the side of the cross member as shown in Fig. 1.

Attached to the end of the insulating strip 17 by an eyelet is a reversely bent contact spring or element 22 which is adapted to resiliently contact with the central terminal 23 of lamp 24 which has its opposite terminal in the form of a threaded base cooperating with the lamp socket 15 of the reflector.

The end of the element 22 is upwardly bent as shown at 25 to form a contact end.

To make and break the circuit to the lamp 90 I employ a finger member 26 on the outside of the casing. This finger member has rivets which pass through slots in the casing and retain between the casing and finger member a friction piece 27 of fiber or other suitable material. Within the casing these rivets are secured to a strip of metal 28 which extends longitudinally and has its upper end bent inwardly and carrying a camming block 28 of insulating material. 100

When the slide is moved upwardly the camming block impinges against a sloping cam edge 29 of the movable contact element 19 and swings the upper end 30 into contact with the end 25 of the fixed resilient contact element 22, thereby establishing a circuit to the lamp. The circuit is broken by a reverse motion of the finger member which withdraws camming block 28 from contact with the movable contact element allowing 110 this element to move to the position shown in Fig. 1 and open the circuit.

The cross member 16 forms a fixed upper abutment for the battery B and prevents the spring pressure from the coil spring reacting through the batteries upon the lamp base. It also prevents shocks which might occur in dropping the flashlight from causing the batteries to impact against the base of the lamp and damage the same. The flexible spring element forms a resilient contact seat for the central lamp terminal and prevents damage to the base in placing the lamp in the reflector.

What I claim is:

1. In a flashlight, a circuit closing device comprising, in combination, a supporting member, a reversely bent spring contact element carried thereby and insulated therefrom, a movable spring contact element carried thereby and insulated therefrom and having an end extending adjacent the end of the first mentioned element and an inclined camming edge, and a sliding member having an insulated contact block upon the upper end thereof and adapted to coöperate 25 with the inclined camming edge of the sec-

ond mentioned element to cam the same into engagement with the first element and close the circuit.

2. In a flashlight, having a lamp therein, comprising in combination, a supporting member, a reversely bent contact element contacting resiliently with the base of the lamp and having an upwardly turned contact making end, a second contact element having an end extending upwardly into co-operative relation with the end of the first contact element and an intermediate inclined camming surface, means for insulating said elements from each other and from the supporting member, means for securing said elements to the supporting member, a finger actuated member having an insulating block thereon, said block being adapted to cam against the camming surface of the second contact element and close the circuit upon the sliding of the finger actuated member.

In testimony whereof I hereunto affix my signature.

GEORGE V. C. VREELAND.
